(57) **CLAIM**

The ornamental design for a set of covers for an infrared sauna heater, as shown and described.

DESCRIPTION

FIG. 1 is front view of a single cover for an infrared sauna heater, shown separately for clarity of disclosure and in a first configuration;

FIG. 2 is a top view thereof;

FIG. 3 is a bottom view thereof;

FIG. 4 is a rear view showing thereof;

FIG. 5 is a left side view thereof;

FIG. 6 is a right side view thereof;

FIG. 7 is a front view of the set of covers for an infrared sauna heater, shown in a second configuration;

FIG. 8 is a front view of the set of covers for an infrared sauna heater, shown in a third configuration; and,

FIG. 9 is a front view of the set of covers for an infrared sauna heater, shown in a fourth configuration.

In the drawings, the broken lines depict environmental structure and form no part of the claimed design.

1 Claim, 5 Drawing Sheets
